(57) **CLAIM**

The ornamental design for a hedge trimmer as shown and described.

DESCRIPTION

FIG. 1 is a front view of a hedge trimmer, shown our new design;

FIG. 2 is a back view thereof;

FIG. 3 is a left view thereof;

FIG. 4 is a right view thereof;

FIG. 5 is a top view thereof;

FIG. 6 is a bottom view thereof;

FIG. 7 is a rear upper perspective view thereof;

FIG. 8 is a rear lower perspective view thereof;

FIG. 9 is a rear perspective view thereof showing the handle turned to the right; and,

FIG. 10 is a rear perspective view thereof showing the handle turned to the left.

Features depicted in broken lines show portions of the head trimmer that form no part of the claimed design.

1 Claim, 10 Drawing Sheets
